US00D804653S

(12) **United States Design Patent** (10) Patent No.: **US D804,653 S**
Clark et al. (45) Date of Patent: ** Dec. 5, 2017

(54) **PRESSURE VESSEL**(71) Applicant: **EMD Millipore Corporation**, Billerica, MA (US)(72) Inventors: **Phillip Clark**, Billerica, MA (US); **Kurt Greenizen**, Billerica, MA (US); **Paul Sydlowski**, Billerica, MA (US); **Christopher A. Scott**, Billerica, MA (US)(73) Assignee: **EMD Millipore Corporation**, Billerica, MA (US)(**) Term: **15 Years**(21) Appl. No.: **29/530,023**(22) Filed: **Jun. 12, 2015**(51) LOC (10) Cl. **24-02**

(52) U.S. Cl.

USPC ..... **D24/121**(58) **Field of Classification Search**USPC D15/121, 123, 224, 176; 604/317-325
CPC . A61M 1/0001; A61M 1/0088; A61M 1/0005

(57) **CLAIM**

The ornamental design for a pressure vessel, as shown.

DESCRIPTION

FIG. 1 is a top perspective view of the pressure vessel;
FIG. 2 is a left side elevation view thereof;
FIG. 3 is a right side elevation view thereof;
FIG. 4 is a front elevation view thereof;
FIG. 5 is a rear elevation view thereof;
FIG. 6 is a top plan view thereof;
FIG. 7 is a bottom plan view thereof;
FIG. 8 is a bottom perspective view thereof; and,
FIG. 9 is a rear perspective view thereof.
The broken line showing of parts of the drawings is included
for the purpose of illustrating use and environment and
forms no part of the claimed design.

1 Claim, 8 Drawing Sheets
